UNITED STATES PATENT OFFICE.

HOWARD B. HASKINS, OF TOLEDO, OHIO, ASSIGNOR TO THE DURA COMPANY, OF
TOLEDO, OHIO, A CORPORATION OF DELAWARE.

LOCK FOR WINDOW REGULATORS.

Application filed November 1, 1926. Serial No. 145,504.

The invention relates to locks and refers more particularly to locks for window regulators to hold the windows in their various positions of adjustment. One of the objects 5 of the invention is to provide a construction of lock the parts of which may be cheaply manufactured and assembled. Another object is to provide a lock having its driving and driven members so constructed that they 10 may be assembled in either of a plurality of positions relative to each other without destroying the operativeness of the lock thereby making the lock more fool proof in assembly. Further objects of the invention 15 reside in the novel features of construction and combinations and arrangements of parts as more fully hereinafter set forth.

In the drawings:

Figure 1 is an interior side elevation of a 20 portion of a vehicle door, partly broken away, and showing a window regulator having a lock embodying my invention;

Figure 2 is an enlarged cross section on the line 2-2 of Figure 1;

Figure 3 is a cross section on the line 3-3 of Figure 2;

Figure 4 is a side elevation of the assembly including the movable parts of the lock.

In the present instance I have shown a 30 vehicle door to which is applied a window regulator having a lock embodying my invention. This vehicle door 1 has an opening in its upper portion and a chamber in its lower portion for receiving the window 2 when lowered from a position closing the opening. 3 is a window regulator for raising and lowering the window and comprising the pivotal lifter arm 4, the crank 5 and suitable mechanism between the crank and the lifter arm for swinging the latter upon rotation of the former. This mechanism includes the gear segment 6 upon the lifter arm, the pinion 7 in mesh with the gear segment and the lock 8 between the pinion and the crank. 40 Both the lifter arm and the lock are mounted upon the mounting plate 9 which is secured to the lock board of the door.

The lock comprises the driving member 10, the driven member 11, the helical spring 12 between the driving and driven members and the stationary sleeve 13 which is normally frictionally engaged by the spring. The driving and driven members and the stationary

sleeve are preferably formed of sheet metal and drawn or stamped to shape. These members are preferably cup-shaped. The base of the stationary sleeve preferably abuts the base of the driving member and is provided with the axially located cylindrical flange 14. The outer end of the stationary sleeve terminates in the outwardly extending annular flange 15 which is rigidly secured to the mounting plate 9. The driving member may be journaled in the stationary sleeve and is connected to the crank 5, while the driven member is journaled in the sleeve and is connected to the pinion 7. 16 is a shaft having a cylindrical portion 17 journaled in the cylindrical flange 14, a reduced portion 18 adjacent to the cylindrical portion for rigid connection with the driving member, and an inner end portion 19 for rigid connection with the crank. The reduced portion 18 is preferably serrated and forced through an axial opening in the base of the driving member and its outer end is preferably peened over upon the base. The driven member 11 is rigidly connected to the pinion 7 by forming in the base of the driven member an axial opening having peripheral recesses corresponding to but slightly smaller than portions of the teeth of the pinion so that when the latter are pressed into the opening in the base of the driven member the pinion will be securely held to the driven member. To provide an extra bearing between the drive and driven members the shaft 16 is provided with the axial reduced extension 20, the outer end of which is adapted to fit within the bore 21 in the inner end of the pinion.

For effecting the driving of the driven member from the driving member I have provided means upon the driving member for initially releasing the helical spring from frictional contact with the stationary sleeve and subsequently rotating the driven member. I have also arranged the parts so that rotation of the driven member forces the helical spring into former frictional engagement with the stationary sleeve to effectively lock the driven member from rotation and thereby hold the window in its adjusted position. In detail, the driving member 10 is provided with a pair of equally spaced fingers 22 extending transversely therefrom toward the driven member. These fingers extend integrally from the an-

nular flange of the driving member and substantially parallel to its axis, and are offset radially inward a sufficient distance to provide clearance for the helical spring. The 5 driven member is also provided with the pair of equally spaced fingers 23 which extend transversely from the driven member toward the driving member and are engageable in the spaces between the fingers 22. These fingers 10 23 also extend integrally from the annular flange of the driven member and substantially parallel to its axis and are offset radially inward a sufficient distance to provide clearance for the helical spring. Furthermore the ends 15 of these fingers 23 abut the base of the driving member 10 to hold the driving and driven members at a predetermined distance from each other. The helical spring surrounds the fingers 22 and 23 between the annular flanges 20 of the driving and driven members and has inturned ends 24 which extend into one of the spaces between the fingers 22 and at opposite sides of one of the fingers 23, the arrangement being such that upon rotation of the driving 25 member one of its fingers 22 engages one of the ends of the helical spring to contract the same and release it from frictional engagement with the stationary sleeve, after which it brings this end into contact with the adjacent 30 finger 23 of the driven member and then rotates the driven member. However, rotation in either direction of the driven member causes its finger 23 located between the inturned ends of the helical spring to engage an 35 inturned end and expand the helical spring into firmer frictional engagement with the stationary sleeve. As a result of this arrangement, the window may be readily raised or lowered upon rotation of the crank but can 40 not be raised or lowered by attempted direct movement of the window.

The fingers of the driving member are diametrically opposite and of the same size so that they are symmetrically arranged and as 45 a consequence the helical spring may be assembled so that its inturned ends are alternatively engageable in either of the spaces between the fingers. The fingers of the driven member are also diametrically opposite and of the 50 same size so that they are symmetrically arranged and as a consequence either of these fingers may be engaged in either of the spaces between the fingers of the driven member and between the inturned ends of the helical 55 spring without affecting or hindering the operativeness of the lock. This facilitates assembly of the members besides making the assembly fool proof.

What I claim as my invention is:

60 1. In a window regulator, the combination of a stationary sleeve, laterally adjacent driving and driven members journaled in said sleeve, said driven member being operatively connected to a window, pairs of diametrical- 65 ly opposite fingers extending transversely

from said driving and driven members, said fingers inter-engaging, and a helical spring within and normally frictionally engaging said sleeve, said spring surrounding said fingers and having inturned ends located between a finger of said driven member and the fingers of said driving member, whereby rotation of said driving member in either direction contracts said spring and releases the same from frictional engagement with said sleeve and through said spring rotates said driven member but rotation of said driven member expands said spring into firmer frictional engagement with said sleeve and locks the driven member from rotation. 70 75 80

2. In a window regulator, the combination of a stationary sleeve, laterally adjacent driving and driven members journaled in said sleeve, said driven member being operatively connected to a window, pairs of symmetrically arranged fingers extending transversely from said driving and driven members, said fingers being alternatively inter-engageable, and a helical spring within and normally frictionally engaging said sleeve, said spring surrounding said fingers and having inturned ends located between either finger of one of said members and the fingers of the other of said members whereby rotation of said driving member in either direction contracts said spring and releases the same from frictional engagement with said sleeve and through said spring rotates said driven member but rotation of said driven member expands said spring into firmer frictional engagement with said sleeve and locks the driven member from rotation. 85 90 95 100

3. In a window regulator, the combination of a stationary sleeve, laterally adjacent driving and driven members journaled in said sleeve, said driven member being operatively connected to a window, pairs of symmetrically arranged fingers extending transversely from each of said driving and driven members, said fingers being alternatively inter-engageable and the fingers of one of said members abutting the other member to space said members from each other, and a helical spring within and normally frictionally engaging said sleeve, said spring surrounding said fingers and having inturned ends located between a finger of said driven member and the fingers of said driving member, said fingers being offset radially inward to provide clearance for said spring, rotation of said driving member in either direction contracting said spring and releasing the same from frictional engagement with said spring and through said spring rotating said driven member but rotation of said driven member expanding said spring into firmer frictional engagement with said spring to lock the driven member from rotation. 110 115 120 125

4. In a window regulator, the combination of a driving member, a pair of equally spaced 130

- 5 fingers extending transversely from said driving member, a driven member operatively connected to a window, a pair of equally spaced fingers extending transversely from 10 said driven member and alternatively engageable in the spaces between the first-mentioned pair of fingers, a helical spring arranged telescopically with respect to all of said fingers and having ends located between 15 either finger of one of said members and the fingers of the other of said members, and a stationary member normally frictionally engaged by said spring, rotation of said driving member in either direction releasing said 20 spring from frictional engagement with said stationary member and through said spring rotating said driven member but rotation of said driven member forcing said spring into firmer frictional engagement with said stationary member.
5. In a window regulator, the combination of a stationary sleeve, a driving member provided with spaced driving portions within said sleeve, a driven member operatively connected to a window and located in substantially axial alignment with said driving member and provided with a plurality of transverse projections alternatively engageable in a space between said driving portions 30 and a helical spring normally frictionally engaging said sleeve, said spring surrounding said driving portions and transverse projections and having inturned ends located between the transverse projection in the space 35 and said driving portions, whereby rotation of said driving member in either direction contracts said spring and releases the same from frictional engagement with said sleeve and through said spring rotates said driven member, but rotation of said driven member expands said spring into normal frictional engagement with said sleeve and locks said driven member from rotation.
6. In a window regulator, the combination of a stationary sleeve, a driving member provided with diametrically opposite spaced driving portions within said sleeve, a driven member operatively connected to a window and located in substantially axial alignment 50 with said driving member and provided with diametrically opposite transverse projections alternatively engageable in the spaces between said driving portions, and a helical spring within and normally frictionally engaging said sleeve, said spring surrounding said driving portions and transverse projections and having inturned ends located between a transverse projection and said driving portions, whereby rotation of said driving 55 member in either direction contracts said spring and releases the same from frictional engagement with said sleeve and through said spring rotates said driven member, but rotation of said driven member expands said 60 spring into firmer frictional engagement 65 with said sleeve and locks said driven member from rotation.
7. In a window regulator, the combination with a stationary sleeve, a driving member journaled in said sleeve and having a pair of diametrically opposite fingers extending transversely therefrom, a driven member operatively connected to a window and located in substantially axial alignment with said driving member and having a pair of diametrically opposite fingers extending transversely therefrom, said fingers interengaging, 70 in a helical spring within and normally frictionally engaging said sleeve, said spring surrounding said fingers and having inturned ends located between a finger of said driven member and the fingers of said driving member, whereby rotation of said driving member in either direction contracts said spring and releases the same from frictional engagement 75 with said sleeve and through said spring rotates said driven member, but rotation of said driven member expands said spring into firmer frictional engagement with said sleeve and locks the driven member from rotation. 80
8. In a window regulator mechanism, the combination with a cup, of a driving member journaled in said cup and having a portion within said cup provided with a recess, a driven member having a projection extending into the recess of said driving member, means extending axially of said driving member for rotatably supporting said driven member, and a coil spring within said cup and arranged to be expanded thereagainst, 85 said coil spring having inturned ends engaging in the recess in said driving member upon opposite sides of said projection. 90
9. In a window regulator, the combination with a cup, of a driving member in said cup provided with a recess, a shaft upon which said driving member is supported, said shaft being provided with an axially reduced portion, a driven member journaled upon said reduced portion and provided with a projection extending within the recessed portion of said driving member, and a coil spring within said cup and arranged to be expanded thereagainst, said coil spring having inturned 95 ends engaging in the recess in said driving member upon opposite sides of said projection. 100
10. In a window regulator, the combination of a stationary sleeve, laterally adjacent driving and driven members, said driven member being operatively connected to a window, said driving member being provided with a portion within said sleeve having a recess, a shaft upon which said driving member is supported, and having an axially reduced portion extending therefrom, said driven member being journaled upon said reduced portion and provided with a projection extending within said recess, and a helical spring within and normally frictionally 105 110 115 120 125 130

engaging said sleeve, said spring surrounding the recessed portion of said driving member and said projection and having inturned ends engaging in the recess in said driving member upon opposite sides of said projection, whereby rotation of said driving member in either direction contracts said spring and releases the same from frictional engagement

with said sleeve and through said spring rotates said driven member but rotation of said driven member expands said spring into firmer frictional engagement with said sleeve and locks the driven member from rotation. 10

In testimony whereof I affix my signature.

HOWARD B. HASKINS.
